UNITED STATES PATENT OFFICE.

JOHN C. CORCORAN, OF ST. PAUL, MINNESOTA.

DENTURE.

973,343.

Specification of Letters Patent. Patented Oct. 18, 1910.

Application filed June 29, 1909. Serial No. 505,051.

To all whom it may concern:

Be it known that I, JOHN C. CORCORAN, a citizen of the United States, residing at St. Paul, in the county of Ramsey and State of Minnesota, have invented certain new and useful Improvements in Dentures, of which the following is a specification.

My invention relates to improvements in dentistry, its object being particularly to 10 provide improvements in that class of dentures which are removably supported in the mouth upon anchoring roots and has among its objects to provide improved means for supporting the denture upon the anchors 15 without the necessity of posts or other securing means extending into the anchor roots.

To this end my invention consists in the features of construction, combination and 20 arrangement of parts hereinafter particularly described and claimed.

In the accompanying drawings forming part of this specification, Figure 1 is a perspective view of a lower maxillary showing 25 my improved denture in place; Fig. 2 is a similar view with the denture removed and illustrating the different steps in the securing of the denture in position; Fig. 3 is a perspective view of a crown; Fig. 4 is a similar view of the same uncompleted; Fig. 5 is a bottom view of the crown; Fig. 6 is a section on line $x-x$ of Fig. 5, and Fig. 7 is a view of the covering plate for the anchor root.

30 In the drawings A represents the tooth roots which constitute the anchors for the removable denture. Any desired number of roots may be used for this purpose and may be natural, transplanted or implanted roots.

35 The root being first properly prepared is surrounded by a band 2 to which is secured a plate 3 covering the top of the root. The plate 3 carries an upwardly extending square abutment 4 formed with a screw threaded 40 opening 5.

B represents a tooth crown which in practice is first formed, as shown in Fig. 4, without a top in order to allow the bottom inset 6 to be formed. The inset 6 is shaped to 45 receive the abutment 4 and has an upwardly extending tube 7. The top or face 8 of the

crown is then suitably secured, as by soldering, to the outer edges of the side wall of the crown and to the tube 7, as indicated in Fig. 6.

55 In the use of the invention the anchor roots for supporting the denture are prepared and fitted with the bands 2 and connected plates 3. The denture to be supported by the anchor roots is prepared by employing the necessary number of crowns B connected by a bridge C, supporting intermediately of the crowns, suitable false teeth 9. The denture is articulated in suitable manner to fit the roots. It is then secured 60 upon the anchor roots by being set over the same with the abutments 4 projecting into the inset openings 6 in the crowns and suitable screws 10 passing through the crowns and into the abutments. In removing or 65 replacing the denture it is only necessary to 70 manipulate the securing screws 10.

75 It will be noted that all of the supporting parts for the denture are supported exteriorly upon the anchor roots without any screws or other features extending into the nerve canals of the roots. This is of particular importance in my invention, insuring the maximum rigidity and simplicity with the minimum of strain or other injurious effect 80 upon the root.

I claim as my invention:

1. In a denture of the class described, an anchor root, a cap inclosing the outer end of said root and formed with a central outwardly extending abutment, a crown having a bottom inset shaped to receive said abutment, and securing means extending through the inset portion of said crown and into said abutment.

90 2. In a denture of the class described, an anchor root, a cap inclosing the outer end of said root and an abutment exteriorly carried by said cap, a crown having a bottom inset shaped to receive said abutment, means 95 forming a structural part of said abutment and crown for preventing rotation of one upon the other and securing means extending through the inset portion of said crown and into said abutment.

100 3. In a denture of the class described, an anchor root, a cap inclosing the outer end

of said root, a rectangular abutment externally carried by said cap, said abutment being formed with a threaded opening, a crown having a bottom inset shaped to 5 receive said abutment, and securing means extending through the inset portion of said crown and into said abutment.

In testimony whereof I affix my signature in presence of two witnesses.

JOHN C. CORCORAN.
